UNITED STATES PATENT OFFICE

2,077,982

REFRIGERATOR

Ralph F. Bixby and John H. Meyer, St. Louis,
Mo.; said Meyer assignor to said Bixby

Application November 5, 1934, Serial No. 751,611

3 Claims. (Cl. 62—91.5)

Our invention relates to refrigerators and has for its main object the provision of an air treating compartment and a storage chamber for foodstuffs both combined in a single cabinet or other casing.

Heretofore, air conditioning apparatus as commonly used in homes has comprised a room cabinet or casing from which treated air was discharged into the space to be cooled. Usually, these cabinets contained a compartment through which the air was circulated over a coil whereby the air was cooled. In some instances these coils were supplied with a heat exchange agent or fluid by a compressor or other means contained in the cabinet, but in other instances the means for providing the agent was located at a remote point in the building. However, in any instance, a cooling agent at a low temperature is available in the cabinet but, before our invention such agent has been used only to cool air passing through the compartment.

As stated above the main object of our invention is to provide a refrigerator including an air conditioning compartment and a storage chamber for foodstuffs both combined in a single cabinet or casing; but our invention has for a further object a provision of such a device which may be manufactured at low cost, but which will be efficient and satisfactory in operation.

While a device embodying our invention, as stated above, may include refrigerating means of any type in the accompanying drawings we have shown our invention embodied in combination with an air conditioning apparatus of the general type described in our co-pending application executed and filed on the same day as this one. In these drawings Fig. 1 is a sectional view in elevation of this embodiment; Fig. 2 is a section 40 along the lines 2—2 in Fig. 1 and Fig. 3 shows a structural detail.

Referring to the figures the embodiment shown therein consists of a cabinet 1 of any suitable shape and design with the interior thereof divided into a compartment 2 through which circulates air being treated, a receptacle 3 for a heat exchange agent and a storage chamber 4 for foodstuffs. The receptacle 3 has associated therewith a container 5 for a low temperature refrigerant such as solidified CO₂.

As explained in my co-pending application the container 5 preferably is of thin metal so as to be in intimate thermal association with the heat exchange agent, such as brine, in the receptacle 3. This agent is circulated by means

of a pump 6, shown in detail in Fig. 3, through a coil 7 positioned in the compartment 2 and, preferably, near a grilled opening 8 through which treated air is discharged from the compartment. Circulation through the inlet openings 9 of the compartment and through the opening 8 in the direction indicated by the arrows in the figures is maintained by a fan 10 of the form shown or by any other suitable mechanical means. The operation of this part of our new and improved device will condition satisfactorily the air in a given space. As described in our co-pending application operation of the pump 6 and the fan 10 may be controlled by any suitable expedient either manually or automatically governed.

The details of construction hereinabove described in connection with this embodiment of our invention may be varied to a great extent because, as explained before, we do not wish to limit our present invention to use with any particular form of air conditioning device.

The essence of our invention resides in providing the storage chamber 4 with such arrangement and adaption that the means for cooling this chamber is the same as the means used to cool the air in a given space and, preferably, the cooling of the chamber is effected independently of operation of the air conditioning apparatus. That is to say, the refrigerant is supplied to the compartment independently of the supply of refrigerant or agent to the coil 7.

Preferably, the chamber 4 is insulated as indicated at 11, but if desired the insulation between the rear wall of the compartment and the outer wall of the receptacle 3 may be eliminated so that the chamber 4 will receive a maxim cooling effect from the agent in said receptacle. A plurality of hollow shelf-like vessels 12 are included in this embodiment with their inner ends opening into the receptacle 3 whereby the heat exchange agent from said receptacle may find its way into the vessels and, although no circulation of agent inside of these vessels is provided for by mechanical means, we have found that the agent in the vessel will be maintained at a low temperature through conduction. Ice trays 13 for freezing water or other liquid may be placed on the vessels 12. In the front of the cabinet there may be provided an opening 14 through which foodstuffs may be introduced into and taken from the chamber 4 and this opening may be closed normally by a door 14.

It will be seen readily that if the elements described above or their equivalents are combined

in a manner as taught by us herein a convenient and easily accessible chamber for storing foodstuffs, beverages and the like is provided and the cooling of such chamber will be effected at 5 virtually no cost.

We do not intend to limit ourselves to the exact details of construction shown in the drawings because the size, shape and arrangement of the various parts may be varied within wide limits 10 without deviating from the spirit of our invention as included in the appended claims.

What we claim as new and desire to secure by Letters Patent, is:—

1. A refrigerator comprising a cabinet having 15 a compartment through which air from outside of said cabinet is circulated to be cooled, said cabinet including a chamber for a low temperature refrigerant arranged to cool a liquid heat exchange agent, means for circulating said heat 20 exchange agent through said compartment for cooling air, and said cabinet also having a storage chamber for food stuffs and means for cooling said storage chamber by said heat exchange agent independently of cooling air in said compartment.

2. A refrigerator comprising a cabinet having a compartment through which air from outside

of said cabinet is circulated to be cooled, said cabinet including a chamber for a low temperature refrigerant arranged to cool a liquid heat exchange agent, means for circulating said heat exchange agent from said chamber and through 5 said compartment for cooling air, and said cabinet also having a storage chamber for food stuffs and means for circulating said heat exchange agent from said chamber through said storage chamber independently of said circulation 10 through said compartment.

3. A refrigerator comprising a cabinet having a compartment through which air from outside of said cabinet is circulated to be cooled, said cabinet including a receptacle for a liquid heat 15 exchange agent, a chamber for a low temperature refrigerant arranged and positioned whereby said refrigerant will cool said heat exchange agent in said receptacle, a coil positioned in said compartment, means for circulating said heat exchange 20 agent from said receptacle through said coil, said cabinet also having a storage chamber for food stuffs and means for circulating said heat exchange agent in said storage chamber.
